FIG. 1.

FIG. 2.

FIGURE 1 is a front perspective view of a bathroom unit, showing our new design.

FIGURE 2 is a fragmentary top plan view taken below the medicine cabinet and above the lavatory.

The rear not shown is substantially plain. The side of the lavatory cabinet not shown is substantially identical to that shown, except as indicated. The side of the water closet not shown is substantially identical to that shown. The top of the wall cabinet is plain.

The dominant features of the design reside in the portions shown in full lines.

We claim:

The ornamental design for a bathroom unit, substantially as shown and described.
